CLAIM

The ornamental design for a portable game target from assembled pieces, as shown and described.

DESCRIPTION

FIG. 1 is a top side perspective view of a portable game target from assembled pieces showing my new design;

FIG. 2 is a bottom plan view thereof;

FIG. 3 is a front end elevation thereof, the front and rear elevations being mirror images of each other;

FIG. 4 is a left side elevation thereof, the left and right elevations being mirror images of each other;

FIG. 5 is an exploded perspective view thereof; and,

FIG. 6 is a top view of the disassembled pieces of my new target.

1 Claim, 2 Drawing Sheets(56)
